TRANSISTORIZED IGNITION UNIT

Fred E. Shindell, Phoenix, Ariz., assignor to
Sidney L. Kosowsky, Phoenix, Ariz.

Filed Feb. 20, 1964, Ser. No. 78,711

Term of patent 14 years

(Cl. D26—13)

FIG.1.

FIG.2.

FIG.5.

FIG.3.

FIG.6.

FIG.4.

FIGURE 1 is a perspective view of a transistorized ignition unit showing my new design;

FIGURE 2 is a top view thereof;

FIGURE 3 is a front view thereof;

FIGURE 4 is an end view thereof and the other end is substantially a mirror image of this;

FIGURE 5 is a rear view thereof; and

FIGURE 6 is a bottom view thereof.

The dominant features of the design reside in the portions shown in full lines.

I claim:

The ornamental design for a transistorized ignition unit, as shown and described.
